UNITED STATES PATENT OFFICE.

WILMER D. GRIDLEY, OF NEW HAVEN, CONNECTICUT.

DESIGN FOR A BRACKET.

Specification forming part of Design No. 5,105, dated July 11, 1871.

To all whom it may concern:

Be it known that I, WILMER D. GRIDLEY, of New Haven, in the county of New Haven and State of Connecticut, have invented or produced a new and original Design for a Bracket, of which the following is a specification:

In the accompanying drawing, Figure 1 is a side elevation of a bracket embodying my design; Fig. 2, a front elevation; and Fig. 3, a top view of the same.

A designates the base, which consists mainly of a group of rhombuses arranged in the form of a rhombus. The shelf B is a part of a circle, the circular edge thereof being bordered by a row of

points, and the body of said shelf being open work in the form of rhombuses. The brace C is also a group of rhombuses, being substantially a section of the base A.

I claim as my invention or production—

1. The design for the whole bracket, substantially as shown and described.
2. The design for the base A, substantially as shown and described.
3. The design for the shelf B, substantially as shown and described.

Witnesses: WILMER D. GRIDLEY.

JAMES SHEPARD,
C. A. SHEPARD.
